UNITED STATES PATENT OFFICE.

GEORGE ADAMS, OF CHICAGO, ILLINOIS.

JOINT FOR METAL BEDS.

No. 923,235.

Specification of Letters Patent. Patented June 1, 1909.

Application filed January 27, 1909. Serial No. 474,391.

To all whom it may concern:

Be it known that I, GEORGE ADAMS, a citizen of the United States, and a resident of Chicago, in the county of Cook and State of Illinois, have invented certain new and useful Improvements in Joints for Metal Beds, of which the following is a specification.

This invention relates to metal beds, and relates particularly to joints for connecting different members of metal bedsteads, or the like, of the general type shown and described in the application of John M. Adams, filed January 8, 1909, Serial No. 471,226.

15 The object of the present invention is to provide improved and simplified means for securing the mold plate in position preparatory to casting the abutment; for connecting the mold plate and abutment so that they will form a substantially unitary structure; and also for preventing all play or relative movement of the connected members of the bedstead.

To effect the foregoing objects, a joint 25 of my invention comprises the various features and details of construction herein-after described and claimed.

In the accompanying drawings, in which my invention is fully illustrated—Figure 1 is 30 a perspective view showing the application of my improved joint for connecting the end of a rod or tube to a hollow member of a bedstead, the mold plate on the inside of the hollow member and the securing means 35 therefor being shown in dotted lines. Fig. 2 is a perspective view of a hollow member of a bedstead, and of a mold plate secured therein, preparatory to forming a joint, the hollow member being partly broken 40 away to expose said mold plate. Fig. 3 is a vertical sectional view on the line 3—3 of Fig. 4. Fig. 4 is a transverse, sectional view on the line 4—4 of Fig. 3; and Fig. 5 is a vertical sectional view showing the application of my improved joint for connecting a corner fastening to a hollow bed post.

Referring now particularly to Figs. 1 to 4 of the drawings, 1 designates a hollow member of a bedstead, or the like, as a top or 50 bottom tube forming part of the framework of the head or foot of a bedstead, usually called "cross tubes", and 2 an upright tube connected thereto, usually called a "filling." The hollow member 1 is provided in its side 55 with a hole or opening 3 adapted to receive the end of the member 2. As shown, the

member 2 fits the hole or opening 3 closely, but my invention contemplates equally holes of larger size, depending upon the desired finish at the joint between said members 1 and 2. Secured in the hollow member 1 is what, for purposes of convenient reference, may be termed a mold plate 4, which contacts with the inner surface of said hollow member around and at a distance from the hole or opening 3 in said hollow member and which is shaped to form a closed recess or cavity 5 into which the hole or opening 3 opens. The mold plate may be made of any suitable metal, being preferably stamped or pressed from sheet steel of suitable thickness, a desirable thickness for ordinary purposes being about 1/16 of an inch. The mold plate 4 is adapted to be secured in position preparatory to casting the abutment 7, 75 which is designed to connect the members 1 and 2 by means of a screw 8 in screw threaded engagement with a hole or opening in said mold plate, the end of which bears against the inside of the hollow member 1 opposite to the hole or opening 3. With the described construction it is obvious that turning the screw 8 with its end in contact with the side of the hollow member 1, the mold plate 4 being held against rotation, 85 will operate to draw said mold plate into close engagement with the inner surface of the hollow member 1 around the opening 3 and will also operate to hold said mold plate firmly in position to form the recess 5. To 90 prevent turning of the mold plate 4 with the screw 8, said mold plate is preferably made longer than the diameter of the hollow member 1.

My invention contemplates making the 95 screw 8 either longer or shorter than the diameter of the hollow member 1, as may be desired, but said screw will, in any event, preferably be made of such length that when turned up to secure the mold plate 4 in position to form the recess or cavity 5, the end of said screw will project into said recess. Where the screw 8 is made shorter than, or substantially equal in length to the interior diameter of the hollow member 1, said 105 screw may be engaged with the mold plate before said mold plate is inserted into said hollow member 1. When, however, the screw 8 is made longer than the interior diameter of the hollow member 1, said mold 110 plate will be first inserted into said hollow member 1 and brought into position with the

screw-threaded opening therein designed for engagement by the screw 8 opposite the opening 3 and said screw is then engaged with said screw-threaded opening through 5 said opening 3.

When the member 2 is hollow, the screw 8 will preferably be provided with a head 9 adapted to enter the bore thereof and to form a plug closing the bore thereof. Said 10 head 9 will thus define the distance which the metal forming the abutment 7 will enter the end of said member 2 when said abutment is cast. While I have, in the drawings, shown the head 9 as formed integral with 15 the screw 8, the object of the invention, as it relates to this feature, can be effected equally well by a separate head or nut threaded to said screw 8 and my invention contemplates this construction as the equivalent 20 of the integral head and by the expression "headed screw" used in the claims, I intend to include either an integral head or a separate head or nut in screw-threaded engagement with said screw.

25 The mold plate 4 having been inserted into the member 1 and secured therein, to form the recess 5 in the manner heretofore described, molten metal, preferably cast iron, is poured into said recess to form the 30 abutment 7. Where the member 2 is closely fitted to the opening 3, one or more gates or pour holes 10 are provided in the member 1 opening into the recess 5. After the abutment 7 has set and hardened, the spuds projecting through the gates or pour holes 10 are dressed off flush with the surface of the member 1.

With the described construction it is obvious that the screw 8, being embedded in 40 the abutment 7 and bearing against the inside of the hollow member 1 opposite to said abutment, said screw will operate to prevent movement of said abutment and thus of the member 2 relatively to the member 1 and 45 will also operate to secure the mold plate 4 and the abutment 7 together so that said mold plate will form in effect a part of said abutment.

In Fig. 5 of the drawings, I have shown 50 my improved joint as applied for securing a corner fastening to the hollow post of a metal bedstead. Referring now to said Fig. 5, 1¹ designates the hollow post of the bedstead, 2¹ the corner fastening member, 3¹ the hole or 55 opening in the post 1¹, 4¹ the mold plate, 8¹ the screw for securing said mold plate in position, said screw being preferably but not necessarily provided with a head 9¹, 7¹ the abutment cast within the recess 5¹ defined 60 by said mold plate 4¹, said abutment being preferably cast integral with the corner fastening member 2¹.

I claim:—

1. A joint for a metal bedstead, or the like, comprising a hollow member provided 65

with a hole or opening, a mold plate, means for securing said mold plate within said hollow member, said mold plate being shaped to form a recess or cavity within said hollow member into which the opening in said hollow member opens, the means for so securing said mold plate in position comprising a screw in screw-threaded engagement with a hole or opening in said mold plate, the end of which is adapted to bear against the inner 70 surface of said hollow member and to draw said mold plate into close engagement with the side thereof around the hole or opening therein, a part of or projection on the other connected member which extends through 75 the hole or opening in said hollow member into the recess or cavity defined by said mold plate, and an abutment cast within said recess or cavity, with or upon said part of or projection on said second connected member 80 which projects into the cavity or recess defined by said mold plate, substantially as described.

2. A joint for a metal bedstead, or the like, comprising a hollow member provided with 90 a hole or opening, a mold plate, means for securing said mold plate within said hollow member, said mold plate being shaped to form a recess or cavity within said hollow member into which the opening in said hollow member opens, the means for so securing said mold plate in position comprising a screw in screw-threaded engagement with a hole or opening in said mold plate, an end of 95 which is adapted to bear against the inner surface of said hollow member and to draw said mold plate into close engagement with the side thereof around the hole or opening therein, said screw being of such length that it will project into the recess or cavity defined by said mold plate, a part of or projection on the other connected member which extends through the hole or opening in 100 said hollow member into the recess or cavity defined by said mold plate, and an abutment cast within said recess or cavity, with or upon 105 said part of or projection on said second connected member which projects into the cavity or recess defined by said mold plate and also upon the end of the screw for securing 110 the mold plate in position which projects into said recess or cavity, substantially as described.

3. A joint for a metal bedstead, or the like, comprising a hollow member provided with 115 a hole or opening, a mold plate, means for securing said mold plate within said hollow member, said mold plate being shaped to form a recess or cavity within said hollow member into which the opening in said hollow member opens, the means for so securing said mold plate in position comprising a headed screw in screw-threaded engagement with a hole or opening in said mold plate, the end of the body portion of which is adapted 120

125

130

to bear against the inner surface of said hollow member and to draw said mold plate into close engagement with the side thereof around the hole or opening therein, said 5 screw being of such length that its headed end will project into the recess or cavity defined by said mold plate, a part of or projection on the other connected member which extends through the hole or opening in said 10 hollow member into the recess or cavity defined by said mold plate, and an abutment cast within said recess or cavity, with or upon said part of or projection on said second connected member which projects into the cavity or recess defined by said mold plate and also upon the headed end of the screw for securing the mold plate in position which projects into said cavity or recess, substantially as described. 15

20 4. A joint for a metal bedstead, or the like, comprising a hollow member provided with a hole or opening, a mold plate, means for securing said mold plate within said hollow member, said mold plate being shaped to 25 form a recess or cavity within said hollow member into which the opening in said hollow member opens, the means for so securing said mold plate in position comprising a headed screw in screw-threaded engagement 30 with a hole or opening in said mold plate, the

end of the body portion of which is adapted to bear against the inner surface of said hollow member and to draw said mold plate into close engagement with the side thereof around the hole or opening therein, said 35 screw being of such length that its headed end will project into the recess or cavity defined by said mold plate, a hollow part of or projection on the other connected member which extends through the hole or opening in said first hollow member into the recess or cavity defined by said mold plate, and over the head of said screw which is of proper size to form a plug therefor, and an abutment cast within said recess or cavity upon said 40 hollow part of or projection on said second connected member which projects into said cavity or recess and which enters the hollow end thereof as far as the plug formed by the head of the screw for securing said mold 45 plate in position, substantially as described. 50

In testimony, that I claim the foregoing as my invention, I affix my signature in presence of two subscribing witnesses, this 22nd day of January, A. D. 1909.

GEORGE ADAMS.
